United States Patent Office.

DAVID N. B. COFFIN, JR., OF NEWTON, ASSIGNOR TO HIMSELF AND IRAH D. SPAULDING, OF BOSTON, MASSACHUSETTS.

Letters Patent No. 98,032, dated December 21, 1869.

IMPROVED CAPSTAN-WINDLASS.

The Schedule referred to in these Letters Patent and making part of the same.

To all whom it may concern:

Be it known that I, DAVID N. B. COFFIN, Jr., of Newton, in the county of Middlesex, and State of Massachusetts, have invented certain Improvements in Capstans and Windlasses; and I do hereby declare that the following is a full and exact description thereof, reference being had to the accompanying drawings, and to the letters of reference marked thereon.

With reference to the drawings—

Figure 1 is a perspective view of my combined capstan and windlass, and illustrating the mode of communicating motion from one to the other.

Figure 2 shows a modification of the cam shown in fig. 1.

Figure 3 shows another modification of this cam, in which a waved form of the groove or flange is illustrated.

Figure 9 illustrates my method of securing the flanged support to all the gears.

Figure 11 illustrates the connecting of the rocking shaft directly to the shackle or link which connects the lever-beam to the pawl-cases or primary levers of the windlass.

Figure 12 illustrates the connecting of the rocking shaft directly to the lever or other vibrating beam.

Figures 13, 14, and 19, illustrate the construction and operation of my locking or sliding bolts with expanded ends, for capstan and windlass-purposes.

Figure 15 shows one of the many modes of pivoting the end of the rocking shaft.

Figure 16 is a view of the other end of the rocking shaft.

Figure 17 shows a roll for the rock-shaft to play in the cam.

Figure 18 shows a shoe for the same purpose.

a is a capstan, of any of the different kinds patented or in use, or otherwise, from which a central shaft, *b*, may be extended, to communicate its motion.

On the shaft *b*, fig. 1, is arranged a cam, *c*. This cam may have a single diagonal groove, as shown in fig. 1, or flanges, as shown in fig. 2, or waved groove or flange, as illustrated in fig. 3, provided, however, that a high point and a low point of the cam-groove or flange shall be opposite in action to each other. This cam has a spherical or partly spherical body, to bear the described cam-groove or flange.

The cam may be secured to the shaft permanently in cases where it is always required when the capstan is used, but in other cases, I furnish the shaft *b* with any suitable clutch or locking-bolts and lifters, (as see fig. 1,) and fit the cam freely upon the shaft, so that it may by these means be readily connected or disconnected to or from the shaft.

When it is only required to use the capstan in one direction without, and the other with the windlass, the

cam may be made to clutch automatically when the capstan is turned in the direction required to operate the windlass, and unclutch when the capstan is turned in the opposite direction. This may be done by automatic sliding bolts similar to those seen in the capstan, fig. 9, or by means of an automatic clutch similar to the one shown in fig. 6, or the one in fig. 4, or otherwise.

A rocking or oscillating shaft, *d*, is arranged to so embrace or engage with the cam *c* as to receive impulse from its two opposite points of action simultaneously, and from each in opposite directions. This not only gives the required rocking or oscillating motion to the shaft *d*, but does it in such a manner that the resistance does not tend to lift or depress the shaft *b* or cam *c*, inasmuch as one side is resisted in one direction with equal force to that with which the other is in the opposite. This brings the strain on the capstan-shaft in the best way to be resisted without liability to displacements of the parts.

A suitable shoe or roller is pivoted to each part of the rocking shaft, near the opposing points of action of the cam, and fitted to act in the cam-groove or upon the cam-flange, as the case may be; only, if the flange is used, rolls or a shoe must embrace it, so as to secure the double or balanced action.

The opposite end of the rock-shaft from the cam may be pivoted, as shown in fig. 15, or furnished with a journal in any convenient manner.

At any convenient point upon the shaft *d*, a suitable head or arms, *e*, are attached by casting or otherwise, and from this head or these arms *e*, the desired reciprocating or vibratory motion is communicated to the pawl-cases or primary levers of a windlass, or to any other device for other required purposes.

The levers *f* represent the pawl-cases, or other primary levers, or other devices for actuating a windlass by means of a vibratory motion.

When it is required to operate the windlass, rotary motion is given to the capstan *a* by means of levers or otherwise, and either with a simple or power-purchase, as the occasion may require, so rotating shaft *b* and cam *c*, and thereby causing shaft *d* to oscillate.

This oscillating or rocking motion of shaft *d* is communicated to the primary levers of the windlass, either by direct connections, or by direct connections to the beam, (see fig. 12,) or to the shackles *g*, which connect the beam to the primary levers *f*, or otherwise, as occasion may require.

In fig. 9 is illustrated my improved mode of securing the proper flange-support for all the gear-teeth, or rather for the teeth of intermediates *s*. These have never been provided with flange-supports to the teeth, owing to the absence of any known facility for applying the same so as to admit of the convenient taking

apart and putting together of the parts of the capstan.

The centre gear is furnished with a space between its teeth, which are flanged at the lower end, and the plate *i* or other adjacent parts, to admit the flange of the intermediates *s*, supporting the upper end of their teeth.

The gears *s* are then fixed upon shafts *v*, having bearings in head *u*, and which may be drawn out freely with the gears *s* when the centre-gear is withdrawn, or instead thereof, studs *w* may be fixed in head *u*, and the gears *s* fitted to turn on, draw off, and slip on them without hindrance, whenever the centre gear is withdrawn, &c.

Figs. 13 and 19 illustrate the construction and useful effect of my improved bolts, with expanded ends for capstan and windlass-purposes.

The expanded ends, it will be noticed, prevent the bolts from slipping when in use. The front giving the proper upright face, and the back coming under the shoulder of the socket, prevent it slipping up, notwithstanding the great looseness allowed, to prevent its rusting in.

The same principle is applied to the automatic bolts seen in fig. 14, to which, however, it is not quite so well adapted, but serves well.

It will be observed that in this description, the terms "upper" and "lower," &c., indicating an upright arrangement of parts, for convenience in the description, do not presuppose that such devices may not be used

under a similar but horizontal arrangement or position, or *vice versa*.

The parts, when not otherwise specified, may be made of the materials ordinarily employed in the construction of capstans and windlasses, or any others filling the conditions required.

Thus having described my invention,

What I claim, and desire to secure by Letters Patent, is as follows:

1. The combination of the capstan-windlass with the double-acting cam and the rocking shaft, substantially as described.

2. The rocking shaft *d*, constructed with wrists and rolls or sliding blocks, (see figs. 16, 17, and 18,) and furnished with arms or head *e e*, in combination with a double-acting cam and shaft, *c b*, substantially as and for the purposes set forth.

3. The combination of the vibrating beam, irrespective of its lever-sockets, with the rocking shaft and pawl-cases or primary levers of the windlass.

4. The arrangement of the flanged intermediate gear or gears *s*, in combination with the space between the teeth of the centre gear and its ratchet-plate or other adjacent part, substantially as described.

5. Constructing the locking or sliding bolts of a capstan, (see figs. 13, 14, and 19,) with expanded ends, substantially as and for the purpose set forth.
